THIMBLE-EQUIPPED INSULATOR

Richard W. Barnitz, Parkersburg, W. Va., assignor
to Porcelain Products, Inc., Findlay, Ohio, a
corporation of Delaware

Application September 12, 1940, Serial No. 356,538

5 Claims. (Cl. 174—200)

The following description relates to a thimble-equipped insulator for high tension electric transmission lines and the thimble itself. Cables for the transmission of high tension electricity are customarily supported on insulators of porcelain or like material which in turn are affixed to vertical pins or other supports. Electrical porcelain is stiff and unyielding and under abnormal conditions may be fractured. It is, therefore, usual to interpose a thin ductile metal thimble between the porcelain and the supporting pin. The thimble is anchored within an axial recess of the insulator and is screw-threaded to receive the screw-thread of the supporting pin. In normal operation the thimble distributes the stresses and protects the insulator from failure.

The use of such a thimble offers some problems incidental to assembly and operation. It is not feasible to produce insulators having axial cavities of precise dimensions. Consequently there is some uncertainty in centering the thimble within the axial recess or chamber. It is also well known that the extended exposed edge of the thimble offers opportunity for the penetration of moisture and deterioration of the cement which is used. This exposed edge of the thimble where it is sharp or thin may cause corona or radio interference. In the assembly of the customary thimbles an excess amount of cement is forced out of the chamber and into the thimble itself. Again due to the usual variation in sizes the amount of cement used may be insufficient to completely fill the chamber around the thimble and thus leave a gap at the exposed base edge of the thimble.

My invention is intended to provide an insulator in which the thimble in assembly is centered without attention. The base edge of the thimble flares outwardly into contact or close fit with the wall of the chamber. It thus effectually seals the cement space, preventing overflow of the cement or penetration of moisture.

A further object of my invention is to provide a rounded, smooth surface for the base flange of the thimble so as to diminish the likelihood of localized electrostatic charges which otherwise might produce corona or radio interference.

A further object of my invention is to materially strengthen the edge of the thimble by doubling the thickness of the metal at that point. Rough handling of the insulator thus is not likely to cause damage to the porcelain or to the thread of the thimble.

As an example of my invention I have shown

its preferred form on the accompanying drawing in which

Fig. 1 is a vertical cross-section of an insulator having my improved thimble and mounted on a pin;

Fig. 2 is an enlarged longitudinal cross-section of the improved thimble;

Fig. 3 is a top plan view thereof, and

Fig. 4 is a fragmentary longitudinal section of 10 a modified form of thimble.

On the accompanying drawing I have shown the improved device to consist of an insulator proper 5. This is made of suitable porcelain and has characteristics permitting it to be used with 15 high tension transmission electric lines. The insulator is supported on a screw-threaded pin 6 of the usual type.

The porcelain insulator has a vertical longitudinal or axial recess 7 which forms a chamber 20 large enough to loosely surround the head of the pin 6. This chamber has a slight taper and the walls may be plain, grooved, sanded or roughened in order to hold a mass of cement 8 without danger of separation. The cement 8 is Portland 25 cement or any other cement suitable for this purpose.

I provide a thimble 9 which is assembled or set 30 within the cement mass 8 while the cement is still plastic. The thimble usually has an internal diameter of 1 to 1 $\frac{1}{8}$ inches. It is made of ductile sheet metal. Zinc is preferred although other equivalent metals may also be used. The sheet is normally approximately one thirty-second of an inch thick. This will permit ready working 35 and forming, by drawing, die-stamping or rolling.

The thimble 9 has a closed top 10. The tapering side wall is corrugated to provide a spiral thread 11 which extends both on the outside and inside surfaces of the tapering side wall. The inner screw-thread is adapted to fit over the screw-thread on the pin 6. The outer groove or thread 40 is interrupted as is the usual practice to provide satisfactory anchorage in the cement. In this manner the thimble is anchored to the insulator and will not be loosened by unscrewing the insulator from the pin.

The lower portion 12 of the side wall is generally cylindrical or conical. Its lower edge is bent out to form a flange or lip 13.

Ordinarily the flange 13 will be further bent 50 backwardly as indicated in Fig. 2 to provide a lip 14. This is spaced parallel to the side wall 12 of the thimble. The length of the lip 14 may vary. It may terminate immediately beyond the curvature of the flange 13 or alternatively it may

be extended substantially. In the latter instance it provides an annular recess 15 which will be of material utility in anchoring the thimble and confining the cement.

I have shown in Fig. 4 the further step by which the lip 14 may be rolled back against the flaring side wall 12. This preserves the flange 13 slightly curved in cross-section and flaring outwardly from the side wall 12. In either case whether the lip 14 is in contact with or parallel to the side wall 12, the same advantages are provided of added strength and freedom from thin, rough edges.

The improved thimble is inserted within the chamber 7 in which the required amount of cement has been placed. The thimble forces the cement around and outwardly from the chamber until it is caught and confined in the annular recess 15. An excess amount of cement will determine the extent to which the lip 14 will fit into the chamber and in contact with its side wall. A deficiency of cement will leave a small vacant space within the recess 15. In either event the lip 14 or more properly the flange 13 will fit snugly around the side wall of the chamber and seal the latter off thus confining the cement and protecting it from penetration of moisture. At the same time the assembly operation necessarily insures proper centering of the thimble.

The provision of a flange greatly improves the appearance of the insulator. At the same time it minimizes the localization of electrostatic charges and will diminish the possibility of corona discharges.

The added strength of the two thicknesses of the sheet material at the point of contact with the insulator helps materially to strengthen the device.

While the preferred form of this invention has been described and illustrated it is believed that the invention is capable of embodiment in various forms, proportions and materials so that it is limited solely by the scope of the appended claims.

What I claim is:

1. An electrical insulator of porcelain or the like, having an axial chamber with a straight

inner side wall, a ductile sheet metal thimble spaced within said chamber, and a basal flange on the thimble extending outwardly and backwardly with the peripheral surface of the backwardly extending portion in contact with the straight inner side wall of the chamber.

2. An electrical insulator of porcelain or the like, having an axial chamber with a straight inner side wall, a ductile sheet metal thimble within said chamber, a body of cement in the chamber around the thimble, a basal flange on the thimble extending outwardly toward the said straight inner side wall of said chamber and a reversely directed extension on the flange having extended contact with the said side wall of the chamber.

3. An electrical insulator of porcelain or the like having a tapering axial chamber with a straight inner side wall, a ductile sheet metal thimble within said chamber, said thimble having its walls corrugated to form internal and external screw threaded grooves, a body of cement in the chamber anchoring the thimble to the insulator, a basal flange on the thimble extending outwardly toward the said straight inner side wall of the chamber, and a reversely directed extension on the flange spaced parallel to the side wall of the thimble and confining a portion of said cement mass.

4. An electrical insulator of porcelain or the like having an axial chamber, a ductile sheet metal thimble positioned within said chamber, said thimble having its wall corrugated to form internal and external screw-threaded grooves and having a diameter less than the diameter of said chamber to provide an annular space between said chamber and said thimble, a body of cement filling said annular space for anchoring said thimble to the insulator, and a flange formed at the base of said thimble and having a reversely directed portion extending back into said axial chamber and having the edge thereof embedded in said annular body of cement.

5. A ductile sheet metal thimble for an insulator having a flanged basal edge of relatively greater thickness than the sheet metal.

RICHARD W. BARNITZ.
